DESIGN FOR A HOLDER FOR PAPER TOWELS OR THE LIKE

Travis O. Smith, Kansas City, Mo.

Application April 23, 1945, Serial No. 119,140

Term of patent 7 years

(Cl. D4—3)

To all whom it may concern:

Be it known that I, Travis O. Smith, a citizen of the United States, residing at Kansas City, in the county of Jackson and State of Missouri, have invented a new, original, and ornamental Design for a Holder for Paper Towels or the like, of which the following is a specification, reference being had to the accompanying drawing forming a part thereof.

Fig. 1 is a perspective view of the holder for paper towels or the like, showing my new design.

Fig. 2 is a front elevational view thereof.

Fig. 3 is a top plan view thereof; and

Fig. 4 is an end elevational view thereof.

I claim:

The ornamental design for a holder for paper towels or the like, as shown.

TRAVIS O. SMITH.
